UNITED STATES PATENT OFFICE.

ARTHUR CARLING, OF HARTFORD, CONNECTICUT, ASSIGNOR, BY MESNE ASSIGNMENTS, TO REYNOLDS SPRING COMPANY, OF JACKSON, MICHIGAN, A CORPORATION OF DELAWARE.

ELECTRIC SNAP SWITCH.

Application filed April 26, 1926. Serial No. 104,819.

The invention relates to an electric snap switch.

The object of the present invention is to provide a simple and comparatively inexpensive electric switch of the snap toggle type which will be strong and durable in construction, easy to manufacture and be capable of a quick make and break and at the same time be positively maintained in its off and on positions.

It is also an object of the invention to provide an electric snap switch of this type which will indicate the position of the oscillatory switch or contact member with relation to the contacts with which it operates.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

30 Figure 1 is a side elevation of an electric snap switch constructed in accordance with this invention.

Fig. 2 is a similar view showing the other side of the electric switch.

35 Fig. 3 is a central vertical longitudinal sectional view.

Fig. 4 is a central transverse sectional view, the operating lever and the oscillatory switch member being in a central alined position.

40 Fig. 5 is a detail perspective view of the body portion of the operating lever.

Fig. 6 is a detail perspective view of the oscillatory switch member.

45 Fig. 7 is a detail perspective view of the supporting member or bracket.

In the accompanying drawing in which is illustrated the preferred embodiment of the invention 1 designates a supporting member or bracket of approximately U-shape, composed of spaced sides 2 and 3 and spaced transverse connecting top portions 4 which provide an intervening opening 5 to ac-

commodate an operating lever 6. The operating lever consists of a body portion having spaced sides 7 and a connecting top portion 8 which is extended to form curved arms 9 projecting in the direction of the swinging movement of the operating lever and bearing the words "on" and "off" and adapted to indicate the position of an oscillatory switch or contact member 10. The supporting member or bracket and the body portion of the switch member are preferably constructed each of a single piece of sheet metal but any other suitable material may, of course, be employed in the construction of the device. The supporting member is provided adjacent the opening 5 with alined bearing openings 11 for the reception of a pivot or fulcrum pin 12 which passes through the said openings 11 and also through alined openings 13 in the sides 7 of the body portion of the operating lever. The operating lever has a limited swing between the transverse connecting portions 4 of the top of the supporting member and the sides of the body portion extend below the pivot or fulcrum pin 12 and are provided with alined bearing openings 14 for the reception of a rocking/guide 15 consisting of a plate having reduced terminal portions forming trunnions 16 which are arranged in the openings 14 and the said plate 15 is provided with a central guide opening 17 through which passes a slideable rod 18 having a head or enlargement 19 adjacent its lower end 20. The rod 18 supports and carries a coiled spring 21 and its lower end 20 is arranged in a central opening 22 in the bottom portion of the oscillatory switch member 10.

The oscillatory switch member consists of a yoke and is approximately U-shaped, its lower or outer portion 23 being reduced in width and adapted to cooperate with spaced contacts (not shown) of the ordinary construction. The sides of the oscillatory switch member are provided at their upper portions with bearing openings 24 and are pivoted to the supporting member 1 by lugs 25 extending laterally from the sides at the center of the lower portions thereof and forming a pivot for the oscillatory switch member. The operating lever is adapted to be oscillated to swing the rocking guide and

the upper end of the rod 18 from one side of the center of the device to the other and the spring will operate as a snap to cause a quick throw of the switch member 10 5 from one position to the other.

One of the sides of the supporting member is provided at one side of the center with a laterally projecting terminal stop lug 27 which limits the swing of the switch 10 member in one direction and the switch member is provided with an approximately L-shaped arm 28 extending from the upper portion of one side of the switch member and projecting inwardly into a substantially 15 segmental recess 29 in the side 2 of the supporting member. The recess 29 is located at the opposite side of the center from the terminal stop lugs 27 and the wall at the upper end of the recess 29 forms a stop 20 which is engaged by the arm 28 and which limits the movement of the switch member in the opposite direction from the terminal lug 27. When swinging the operating lever to actuate the switch member to carry the 25 same to its open position the operating lever is adapted to contact with the arm 28 and positively kick off the oscillatory switch member so that there will be no liability of the switch member becoming frozen in its 30 closed position.

The operating lever is provided with a shank 30 having a head or button 31 of suitable insulating material and suitably secured to the top portion of the operating 35 member centrally thereof.

The switch is simple, practical, compact and inexpensive and is positive and reliable in its operation. It is adapted to produce a quick movement of the oscillatory switch 40 or contact member and it produces a positive kick off in the movement of the oscillatory member from its closed position and the spring 18 which is compressed in the movement of the switch member from one 45 side of the center to the other positively maintains the switch member in each of its positions.

What I claim is:

1. An electric switch including a supporting member, comprising spaced sides and a connecting top portion provided with an opening, one of the sides at one end having a laterally projecting terminal stop lug and at the opposite end having a substantially 55 segmental shaped recess, the sides each having a lug extending laterally therefrom at the center of the lower portion thereof and forming pivots, an oscillatory switch member approximately U-shaped with the sides 60 of the same at their inner portions directed outwardly, resulting in the outer portion of

the switch member being reduced in width, said outwardly directed portions of said arms of the switch member at their free ends having bearing openings engaging over the 65 aforesaid pivot lugs of the supporting member, one of the arms of the switch member having an inwardly directed element projecting into the aforesaid segmental shaped recess in one side of the supporting member for cooperation with one end of said segmental recess to limit swinging movement of said switch member in one direction and the aforesaid stop lug on one side of the supporting member limiting the movement of 70 the switch member in the opposite direction, an operating lever pivoted between the sides of the supporting member and a spring connection between the switch member and the operating lever, the aforesaid inwardly directed element projecting from one of the arms of the switch member extending into the path of the operating lever to provide a positive "kick-off" for the switch member. 75

2. An electric switch including a supporting member comprising spaced sides and a connecting top portion provided with an opening, one of the sides at one end having a laterally projecting terminal stop lug and at the opposite end having a substantially 80 segmental shaped recess, including a straight edge, the sides each having a lug extending laterally therefrom at the center of the lower portion thereof forming pivots, an oscillatory switch member approximately U-shaped, the arms of which have bearing 85 openings in their free ends engaging over the aforesaid pivot lugs of the supporting member, one of the arms of the switch member having an inwardly directed element projecting into the aforesaid substantially segmental shaped recess in one side of the supporting member for cooperation with the straight edge of said substantially segmental shaped recess adjacent the inner end of the latter to limit swinging movement of the switch member in one direction, the aforesaid stop lug on the supporting member arresting movement of the switch member to 90 limit the movement of the switch member in the opposite direction, an operating lever pivoted between the sides of the supporting member, and a spring connection between the switch member and the operating lever, the said inwardly directed element projecting from one of the arms of the switch member extending into the path of the operating lever to provide a positive "kick-off" for the switch member. 95

In testimony whereof I have hereunto 100 set my hand.

ARTHUR CARLING.
